UNITED STATES PATENT OFFICE.

CHARLOTTE G. SIMPSON, OF NEW YORK, N. Y.

PORTABLE CABINET.

SPECIFICATION forming part of Letters Patent No. 657,463, dated September 4, 1900.

Application filed May 1, 1900. Serial No. 15,149. (No model.)

To all whom it may concern:

Be it known that I, CHARLOTTE G. SIMPSON, a citizen of the United States, and a resident of the city of New York, borough of Manhattan, in the county and State of New York, have invented a new and Improved Portable Cabinet, of which the following is a full, clear, and exact description.

This invention relates to portable or other cabinets employed for holding family medicines or other articles, and has for its object to provide a novel, simple, and very convenient cabinet which may be readily carried from point to point or be held stationary, as may be preferred, it being well adapted to receive and hold for quick removal a large number of vials containing various medical preparations, and also receive a number of different articles of family use, all disposed in compact order for ready access thereto, as occasion may require.

The invention consists in the construction and combination of parts, as is hereinafter described, and defined in the appended claims.

Reference is to be had to the accompanying drawings, forming a part of this specification, in which similar characters of reference indicate corresponding parts in all the figures.

Figure 1 is a perspective view of the cabinet having its doors open, exposing interior details of construction and various articles held in the cabinet. Fig. 2 is a sectional side elevation taken on a center line with one door closed. Fig. 3 is a sectional plan view showing the doors of the cabinet partly opened, taken substantially on the line 3-3 in Fig. 2. Fig. 4 is a reduced perspective view showing the cabinet closed. Fig. 5 is a sectional side elevation of a holder-case and a side view of a graduated liquid measure held in said case; and Fig. 6 is a side view of a funnel that is one of the essential implements stored in the cabinet for the filling of bottles when desired.

In the drawings which illustrate the construction and application of the invention, 7 indicates the casing or walls of the cabinet, which may be of any suitable material. As 50 shown, the greater portion of the casing 7 is rectangular in contour and somewhat elongated to adapt it for the reception of another

principal feature of the invention which will be described presently.

The end walls of the cabinet-casing are extended above the free edges of the sides thereof, and said end extensions are rounded upon their free edges, as clearly shown in Fig. 1. Preferably two similar doors 8 are provided to close one side of the casing 7, and one edge 60 of each door is hinged upon a corresponding edge of one side wall of said casing, as indicated in Figs. 3 and 4.

In some cases I may prefer to construct the cabinet-casing and the doors therefor of a light strong material which is slightly yielding—such as sole-leather, stout waterproof pasteboard, or equivalents thereof—and to give finish to the exterior I may cover the same with a strong fibrous material, such as billiard-cloth or the like. In the event that a cloth covering or its equivalent is provided as an outer surface for the cabinet-body and the doors said material may be utilized to afford a hinged connection for each door 8 75 with the cabinet-casing, as is clearly shown in Fig. 3. I may also provide hinges a to connect each door 8 with a respective edge of the cabinet-body, as represented in Fig. 4, either method of hinging the doors upon the cabinet-body being available.

The doors 8 are curved so as to render their inner surfaces concave, the degree of curvature thereof adapting said doors to fit at their ends upon the convex upper edges of 85 the end walls of the casing 7 when the doors are closed. Upon each end of each door 8 a depending flange 8^a is formed or secured, which flanges have a loose contact upon the outer surfaces of the end walls of the cabinet 90 when the doors are fully closed, as shown for one end of each door in Fig. 4, and the latter may be secured in close adjustment by any suitable means.

Within the casing 7 a peculiarly-constructed bottle and jar carrier is located, which is constructed essentially as follows: A preferably-three-part hollow column 9 is held to rotate in a vertical position upon a base-plate 10 by a spindle b, which passes down through a tubulation b', formed or secured at the junction of three tubes of preferably-equal diameter, which together form the column 9. The upper end of the spindle b is loosely secured

in an open-slotted box *c*, that is fixed upon the inner side of the end wall of the casing 7, which is uppermost when the device is supported upright upon the opposite end of the casing, as shown in Fig. 1. Upon the column 9 two similar galleries 11 11^a are held at proper points, the lower gallery 11 being affixed upon the column near its lower end, having clearance from the base-plate 10. The uppermost 10 gallery 11^a is removably held in position a proper distance above the lower gallery by a plurality of angle-brackets *d*, that project from the column 9, as shown in Figs. 1 and 2. The galleries 11 11^a are essentially annular, 15 having each a trefoil central aperture therein, so that the galleries loosely fit upon the exterior of the column 9, and the outer wall of each gallery is substantially circular, as indicated in Fig. 3. A suitable number of pockets *e*, formed by division-walls *e*, are disposed completely around the space defined within the peripheral wall of each gallery 11 11^a, these pockets varying in capacity to adapt them to hold bottles 12 and jars 13 of different 20 diameters. The bottles 12 must in service be properly labeled, and to this end a pack of label-blanks *g* may be held in a flap-pocket 14, located upon one of the doors 8 at its inner side, as indicated in Fig. 1, so that an appropriate label may be placed on a bottle containing a medical preparation, and thus avoid mistake when any of the different medicines 25 is to be administered. In Fig. 1 I have shown one bottle 12^a, wherein poison may be held, the bottle being provided with a notched cork and a pendent chain supporting a ball or the like on the free end thereof to serve as a warning when any of the medicines are to be given to a patient needing the same. The jars 13 30 may contain unguents or cerates of different kinds, which are used for local application, such as salves for the cure of skin eruptions or for the cure of cuts, bruises, or burns. It will be obvious that by the special construction and arrangement of the rotatable upright column 9 and galleries thereon any bottle or jar held in either gallery 11 11^a may be quickly brought into view and the label read before taking the bottle or jar from the pocket 35 containing the same.

To facilitate the rotation of the bottle and jar carrier, I prefer to locate antifriction-rollers *h* upon the upper side of the flat base-plate 10, which rollers will engage with the 40 bottom wall of the lower gallery 11 near its periphery, and thus facilitate the revoluble movement of the column and galleries.

Within each of the three tubular sections of the column 9 bottles of washes or other 45 medical preparations may be placed, said secret receptacles being particularly available for the storage of such articles as are not to be commonly used.

In the corners of the casing 7, at each side 50 and rearward of the vertical bottle-carrier, room is afforded for the retention in compact condition of bandages, sterilized cotton, lint,

or the like for dressing sores or fresh wounds, one such package being represented in Fig. 3 at one corner held removably by a keeper-band *k*, a syringe appearing in section in the opposite corner held by a looped band *m*. The flap-pocket 14 may also contain a graduated measuring vessel *w*, that for protection is removably held in a fibrous casing *w'*, this device appearing full-sized in Fig. 5, and it is obvious that any other small article may occupy vacant space in the pocket 14. Below the flap-pocket 14 a similar pocket 15 is secured on the inner side of the door 8, this 55 pocket, which is somewhat deeper than the upper pocket, being subdivided, and thus rendered available for the retention in place ready for service of small implements, which are of service as adjuncts to the curative preparations held in other parts of the cabinet and may comprise a spoon *n*, bottle-brush *n'*, pencil *n*² for marking labels, a cork-screw *n*³, liquid-dropper *n*⁴, and throat-brush *n*⁵, as shown in Fig. 1. At the inner side of the other door 8 a flap-pocket 16 is located, which is preferably employed for the convenient stowage 60 therein of a flexible urinal *o*, having hose *o'* attached for use by bed-fast patients.

Upon the inner side of the bottom wall of the casing 7, which when the cabinet is set upon one end for use becomes the back wall thereof, a hot-water bag *p* may be held, there being sufficient space between the bottle-carrier and said back wall to admit the bag, as is clearly shown in Fig. 2. Near the syringe that occupies one corner of the cabinet, as before explained, and in front of the same, a small funnel *r* is held, which is useful in case the contents of one bottle are to be decanted into another bottle or a replenishment of liquid medicine is to be introduced into any one of the bottles which may be empty.

Upon the lower side of the end wall of the casing 7, which becomes uppermost when the cabinet is in an erect position, a plurality of pockets *s*, *s'*, *s*², *s*³, *s*⁴, *s*⁵, and *s*⁶ are positioned, which may be utilized for the holding of several useful articles—as, for example, a pin-box, scissors, thermometer, roll of sterilized bandage material, and elastic bands for securing the bandage in place—and a box held in one of the pockets may contain small gum bands of different sizes for binding bandages upon an injured member, such as a finger or toe.

It will be seen that by provision of the described means for placing the bottle-carrier 9 within the casing 7 its quick and convenient removal therefrom may be effected, so as to permit access to the articles placed behind it in the casing. Furthermore, the removal of the bottle-carrier enables one to get at a bottle or the measuring-glass that occupies one of the tubular members of the column 9 with ease and replace the same when this is desired.

It is a feature of novelty and merit possessed by this improved cabinet that it is

not only adapted to be placed upon one end and be used as a stationary receptacle having doors, but also is capable of being closed up, so as to be carried as a hand-trunk, a handle 5 8^b, that is secured upon one door 8, affording means for its convenient portage.

The simplicity, compactness of interior details which afford means for utilizing all the interior space, and the very practical nature 10 of the improvement are manifest features of the same.

Having thus described my invention, I claim as new and desire to secure by Letters Patent—

15 1. In a portable cabinet, a casing having hinged doors and a rotatable carrier therein comprising a three-part hollow column adapted to hold articles, a central spindle removably engaging supports in the casing, and 20 passing through an opening where the three portions of the column join, and spaced galleries held on the tubular column.

2. In a portable cabinet, a casing having hinged doors, and a rotatable carrier therein comprising a three-part tubular column, closed at the bottom and open at the top for reception of goods, a spindle passing through an opening at the center of the hollow column 25 where its three portions join, and encircling 30 galleries held upon the column at spaced distances apart, each gallery having a plurality of pockets formed by spaced partitions, a bottom wall, and an exterior side wall.

3. In a portable cabinet, a casing, doors on 35 one open side of the casing, and a rotatable carrier in the casing, comprising a three-part tubular column open at the upper end for reception of articles, a supporting-spindle passing through a small tubulation at the center 40 of the hollow column upon which the three hollow portions of the column are affixed, a removable base-plate, in which the lower end of the spindle is stepped, a slotted bracket-box on the opposite end of the casing within 45 it adapted to hold the upper end of the spindle removably, and a plurality of galleries mounted at intervals upon the tubular column for rotation therewith.

4. In a portable cabinet, the bottle-holding 50 device comprising a three-part tubular column

open at the upper end for reception of articles, a longitudinal tubulation at the center and whereon the three portions of the hollow column are joined, a spindle passing through the tubulation, a base-plate in which the 55 lower end of said spindle is stepped, two galleries each having a plurality of pockets and encircling the column, one at the lower end and one above said lower gallery, each gallery having a plurality of pockets formed by 60 spaced partitions, and a set of antifriction-rollers intervening the bottom wall of the lower gallery and the base-plate.

5. A portable cabinet, having a body of stiff material, the ends of which extend above 65 the sides and are rounded at the upper edges, curved doors hinged to the side edges of the body, the body and doors forming a handbag, and a rotary carrier for bottles, jars and the like, the carrier being mounted on an axis 70 ranging longitudinally of the cabinet and having compartments ranging lengthwise of the carrier at points around the axis and being closed except at an end facing an end of the cabinet, to hold the contained bottles and 75 the like in an upright position when the cabinet is on end, all as shown and described.

6. A portable cabinet, having a body of stiff material, the ends of which extend above 80 the sides and are rounded at the upper edges, curved doors hinged to the side edges of the body and provided interiorly with flexible pockets, the body and doors forming a handbag, and a rotary carrier for bottles, jars and the like, the carrier being mounted on an axis 85 ranging longitudinally of the cabinet and having compartments ranging lengthwise of the carrier at points around the axis and being closed except at an end facing an end of the cabinet, to hold the contained bottles and 90 the like in an upright position when the cabinet is on end, all as shown and described.

In testimony whereof I have signed my name to this specification in the presence of 95 two subscribing witnesses.

CHARLOTTE G. SIMPSON.
